(57) **CLAIM**

The ornamental design for a refrigerator with transitional graphical user interface, as shown and described.

DESCRIPTION

FIG. 1 is a front view of the refrigerator with transitional graphical user interface showing a first image in a sequence, showing our new design;

FIG. 2 is a front view showing a second image thereof;

FIG. 3 is a front view showing a third image thereof;

FIG. 4 is a front view showing a fourth image thereof;

FIG. 5 is an enlarged view of the encircled portion in FIG. 1;

FIG. 6 is an enlarged view of the encircled portion in FIG. 2;

FIG. 7 is an enlarged view of the encircled portion in FIG. 3; and,

FIG. 8 is an enlarged view of the encircled portion in FIG. 4.

The broken line illustrating portions of the refrigerator forms no part of the claimed design. The broken lines illustrating portions of the transitional graphical user interface form no part of the claimed design. The dot-dot-dash broken lines encircling enlargement portions of the design form no part of the claimed design. The appearance of the transitional image sequentially transitions between the images shown in FIGS. 1-4. The process or period in which one image transitions to another image forms no part of the claimed design.
